(57) **CLAIM**

I claim the ornamental design for a safety beacon, as shown and described.

DESCRIPTION

FIG. 1 is a front view of a first embodiment of the claimed design in an open configuration;

FIG. 2 is a rear view thereof;

FIG. 3 is a right side view thereof;

FIG. 4 is a left side view thereof;

FIG. 5 is a top view thereof;

FIG. 6 is a bottom view thereof;

FIG. 7 is a front perspective view thereof;

FIG. 8 is a rear perspective view thereof; and

FIG. 9 is a front perspective view thereof in a closed configuration.

FIG. 10 is a front view of a second embodiment of the claimed design in an open configuration;

FIG. 11 is a rear view thereof;

FIG. 12 is a right side view thereof;

FIG. 13 is a left side view thereof;

FIG. 14 is a top view thereof;

FIG. 15 is a bottom view thereof;

FIG. 16 is a front perspective view thereof;

FIG. 17 is a rear perspective view thereof; and,

FIG. 18 is a front perspective view thereof in a closed configuration.

The broken lines in the drawing views show portions of the safety beacon that form no part of the claimed design. The shade lines in the drawing views show contour and not surface ornamentation of the safety beacon.
